UNITED STATES PATENT OFFICE.

ANDREW J. NEAFIE, OF MOUNTAIN LAKES, NEW JERSEY, ASSIGNOR TO THE RAIL JOINT COMPANY, OF NEW YORK, N. Y., A CORPORATION OF NEW YORK.

REVERSIBLE SPLICE BAR FOR RAIL JOINTS.

Application filed May 3, 1924. Serial No. 710,896.

To all whom it may concern:

Be it known that I, ANDREW J. NEAFIE, a citizen of the United States, residing at Mountain Lakes, in the county of Morris 5 and State of New Jersey, have invented certain new and useful Improvements in Reversible Splice Bars for Rail Joints, of which the following is a specification.

This invention relates to the subject of 10 rail joints, and more particularly to a construction of splice bar wherein a perfectly balanced distribution of metal is maintained, and provision made for obtaining maximum wear from the bar.

15 To that end the invention contemplates a splice bar of a truly symmetrical form, and so designed, that it possesses the capacity of reversibility in four ways thus obtaining a prolonged life and wear from the bar, also 20 effecting substantial economy in track maintenance because of the several positions in which the bar can be used to present unworn bearing surfaces when certain of the bearing surfaces have been worn sufficiently 25 to be unsuitable for engagement with the head and base flange of the rail.

With these and other objects in view which will be readily apparent to those familiar with track conditions and track main- 30 tenance the invention consists in the novel splice bar construction illustrated and de- scribed and claimed.

The drawings here present a practical embodiment of the invention and in these draw- 35 ings—

Figure 1 is a sectional view showing the improved reversible splice bar applied in operative relation to a rail within the fishing space thereof.

40 Figure 2 is a perspective view of the im- proved bar.

Like references designate corresponding parts in the separate figures of the draw- 45 ings.

The improved splice bar construction in- 50 volves rolling a billet into the form of a symmetrical I-bar. This I-bar is designated in the drawings by the numeral 1 and con- sists of a substantial web portion 2 of a uni- form width and having the parallel side faces 3—3, and formed integrally with both longitudinal edge portions of the web are

the duplicate and symmetrical head mem- 55 bers 4—4. Each head member 4 of the splice bar is provided thereon with the in- clined bearing faces 5—5 which converge toward each other to a common apex 6 lying in a vertical plane intersecting the vertical center of the bar. The said oppositely in- clined bearing faces 5—5 are disposed at the 60 same angle and are of the same area, and be- yond each bearing face 5 the head member of the bar is projected outwardly beyond the adjacent side face 3 of the web to form a reinforcing rib 7, and between upper and 65 lower reinforcing ribs 7 at the same side of the bar is formed in the bar a bolting chan- nel or recess 8 adapted to receive therein a bearing or equivalent washer 9 for the nut 10 of the bolt 11, and as shown, the 70 major diameter of the nut is longer than the adjacent side wall 3 of the web thus involving a structure wherein the ribs 7 are disposed sufficiently near the bolt holes 75 as to greatly improve the section modulus of the bar above and below the horizontal neutral axis.

By reason of the fact that the splice bar is of exactly similar construction upon both 80 sides of its vertical central longitudinal axis, it is truly symmetrical and is revers- 85 ible in four ways so that any of the four similar bearing faces 5 may be presented for engagement with either the under side of the head of the rail or with the upper side of the base flange of the rail, thus ob- taining greatly prolonged life of the splice bar, and permitting the track to be main- 90 tained at the joints with the greatest economy.

It will further be observed that by reason 95 of the truly symmetrical form of the con- struction the modulus of the top and bot- tom portions of the bar are the same as well as the modulus of the bar respectively above and below the horizontal neutral axis. This provides a perfectly balanced bar and one in which a substantial head strength can be maintained.

From the foregoing it is thought that the 100 invention will now readily be understood, and also that minor changes may be re- sorted to without departing from the spirit or scope of the invention.

I claim:—

A rail joint splice bar of symmetrical I-bar formation throughout and including duplicate and symmetrical head members having ribs projecting laterally beyond the sides of the web and formed with similar inclined rail bearing faces all of the same area and inclination, and each pair of said

bearing faces converging to an apex lying in the plane of the longitudinal vertical center of the bar, thereby permitting the bar to be reversed in four ways. 10

In testimony whereof I hereunto affix my signature.

ANDREW J. NEAFIE.
